(57) **CLAIM**

The ornamental design for a positive airway pressure delivery console, as shown and described.

DESCRIPTION

FIG. 1 is a front perspective view of a positive airway pressure delivery console showing a first embodiment according to our new ornamental design;

FIG. 2 is front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is another front perspective view thereof;

FIG. 9 is yet another front perspective view thereof on an enlarged scale;

FIG. 10 is a front perspective view of a positive airway pressure delivery console showing a second embodiment according to our new ornamental design;

FIG. 11 is front view thereof;

FIG. 12 is a rear view thereof;

FIG. 13 is a top view thereof;

FIG. 14 is a bottom view thereof;

FIG. 15 is a right side view thereof;

FIG. 16 is a left side view thereof;

FIG. 17 is another front perspective view thereof; and,

FIG. 18 is yet another front perspective view thereof on an enlarged scale.

The broken lines represent environment or structure and do not form a portion of the claimed design.
